United States Patent Office.

GEORGE J. STURDY AND S. W. YOUNG, OF PROVIDENCE, RHODE ISLAND.

Letters Patent No. 80,236, dated July 21, 1868.

IMPROVEMENT IN JAPANNING METALS.

The Schedule referred to in these Letters Patent and making part of the same.

TO ALL TO WHOM IT MAY CONCERN:

Be it known that we, GEORGE J. STURDY and S. W. YOUNG, of Providence, in the county of Providence, and State of Rhode Island, have invented a new and useful Improvement in Japanning Metals; and we do hereby declare that the following is a full, clear, and exact description thereof, which will enable those skilled in the art to make and use the same, reference being had to the accompanying drawings, forming part of this specification.

This invention relates to improvements in japanning, and is applicable to all metals and to all articles which have usually been heretofore subjected to the japanning process, but more especially to the smaller and more delicate class of articles, as eyelets, hooks and eyes, buttons, &c., where the obstacles and objections to the present imperfect method of japanning are more frequently met with.

In japanning eyelets by the old method, it has been found utterly impossible to perform the operation without leaving a surplus of the japan adhering to the articles.

This renders them liable to stick together, and requires a tedious operation to separate them, generally requiring hand-labor and much manipulation to prepare them for market or use.

At best there is left a thick, black, and uneven coating on the surface, which gives them a clumsy appearance.

But this is not the principal objection to them.

These eyelets are used mainly in the shoe-trade, and are set by machinery.

The surplus japan gums up the dies and machinery employed in the operation, and thereby occasions much trouble and delay.

To overcome these difficulties, and to give the eyelets a better color, and much neater appearance, and to perform the process of japanning eyelets, as well as other articles, at far less expense, is the object of our present invention.

This we accomplish, not only by the use of new and important additions to the materials ordinarily used in japanning, but by pursuing a new and improved method in performing the operation.

Our invention consists—

Firstly, in covering the cyclet or article to be japanned with a coating of plumbago or black lead, or other equivalent substance. This we do by agitating or revolving the article (in mass) in the rattling-box, in combination with the powdered plumbago or black lead.

Secondly, we immerse the article in a solution of asphaltum, japan, and naphtha, or turpentine, or any equivalent volatile substance. This is done with the article and solution in a cold state, but if the temperature of the solution were raised, a similar result might be produced. We do not, therefore, confine ourselves to a cold temperature for this part of the process. The article is then taken from the solution and drained.

Thirdly, the article is next immersed in water, and the temperature is raised sufficiently to vaporize the naphtha or other volatile liquid which may be in combination with the japan-coating, and to separate from the article all the extra or surplus japan, which will readily float upon the surface of the water.

The article is then turned out in mass into wire or perforated pans, and subjected to a temperature of from 200° to 600° Fahrenheit, a sufficient length of time, when the process is complete.

The process may be repeated if deemed necessary, but in ordinary cases one operation is sufficient.

The article, when thus japanned, is of the color of rubber or bronze, and presents a bright and neat appearance, free from all surplus japan, perfectly dry, and without any more tendency to stick together than it had before the operation commenced.

Aside from the great superiority of the article we produce, we greatly reduce the expense of japanning by our process.

We claim as new, and desire to secure by Letters Patent—

1. The use of plumbago, or its equivalent, in the process of japanning, substantially as described.

2. Immersing the article japanned in a water-bath, thereby setting free the naphtha, or other volatile liquid, and throwing off the excess of japan, substantially as described, and for the purposes set forth.

3. The black-lead coating, or its equivalent, in combination with a hot-water bath, in the process of japanning, substantially as described.

GEORGE J. STURDY,
S. W. YOUNG.
